UNITED STATES PATENT OFFICE.

LUIGI BRUNACCI, OF NEW YORK, N. Y.

ELECTRIC SAFETY-RAZOR.

No. 911,472.

Specification of Letters Patent.

Patented Feb. 2, 1909.

Application filed June 27, 1908. Serial No. 440,617.

To all whom it may concern:

Be it known that I, LUIGI BRUNACCI, a subject of the King of Italy, and a resident of the city of New York, borough of Manhattan, in the county and State of New York, have invented a new and Improved Electric Safety-Razor, of which the following is a full, clear, and exact description.

This invention relates to safety razors such as used by men in shaving.

The object of the invention is to produce a razor of simple construction having blades operated by electrical means, and shielded in such a way that they may be applied to the face without danger of cutting the skin.

The invention consists in the construction and combination of parts to be more fully described hereinafter and particularly set forth in the claims.

Reference is to be had to the accompanying drawings forming a part of this specification in which similar characters of reference indicate corresponding parts in all the figures.

Figure 1 is a side elevation and longitudinal section through the device, the section being taken on the line 1—1 of Fig. 2 through the drum of the device; Fig. 2 is a cross section taken on the line 2—2 of Fig. 1; Fig. 3 is a plan showing a modified construction for securing the drum in position; and Fig. 4 is a perspective showing the blade holder and illustrating the manner of constructing the same, and the manner of securing the blades thereto.

Referring more particularly to the parts, 1 represents the drum, barrel, or guard of the device, which is of cylindrical form, as shown. This drum is formed of light sheet metal or similar material, and its lower half is solid that is, it is imperforate, as indicated in Fig. 2. The upper half of the drum or barrel is provided with a plurality of inclined slots 2, as indicated in Fig. 1. These slots are disposed quite close together so that this part of the barrel presents a plurality of inclined guard bars 3.

The barrel 1 is provided at its inner extremity with a threaded neck 4 which is adapted to be screwed into a substantially circular head 5. Through this head passes a shaft 6 which is an extension of the shaft of an electric motor 7, said motor being attached upon a bracket 8 projecting from the lower edge of the head 5, as indicated. To this bracket the handle 9 is attached, by

which the razor is held in shaving. At the lower end of this handle 9, an electric cord 10 passes into the same, and by means of a switch 11, the current may be turned off or on through the motor. The head 5 is a part of the bracket 8 and is offset from the axis of the handle; the motor is seated centrally on the axis of the handle.

The outer end of the barrel 1, is provided with an integral head 12. The shaft 6 extends through this head and its projecting extremity is provided with a removable thumb nut 13, which holds the barrel in position, as will be readily understood. On the inner side of the head 5, a washer 14 is received, and this washer is formed with a centrally disposed boss 15 which projects into the interior of the barrel and around the shaft 6, as indicated. Within the barrel, on the shaft 6, there is fixed a blade holder 16, the construction of which is most clearly shown in Fig. 4. This blade holder presents two oppositely disposed cross heads 17, the outer ends of which are connected by curved cheek plates 18. The outer edges of these cheek plates 18 are bent over so as to form flanges or lips 19, which are adapted to receive the ends of the razor blade 20, as shown. These cheek plates near their middle parts are provided with short circumferential slots 21, which facilitate the attachment of the blades in position. The blades are curved, as shown, and their cutting edges 22 project beyond the forward side of the cross head 17 with respect to the direction of rotation. Each blade is provided with a clamping screw 23, which projects inwardly through the slot 21 so as to receive a clamping thumb nut 24, as shown in Fig. 4. The slots 23 enable the blades 20 to be adjusted as desired, so that they will lie just within the wall of the barrel. The curvature of the blades and cheek plates is such that the blade handle fits nicely within the barrel, as indicated in Fig. 2, with the cutting edges presented quite close to the inner side of the barrel wall.

In using the razor the barrel is applied to the side of one's face. The hairs of the beard protrude through the slots into the interior of the barrel and are cut off by the blades as the blade holder rotates. It will of course be understood that the hubs 25 of the cross heads fit snugly on the shaft 6, so that when the shaft rotates the blade holder will also rotate. The blade holder is prevented from shifting longitudinally on the shaft 6, be-

cause it is held between the end of the boss 15 and the fixed head 12, as indicated in Fig. 1.

Instead of attaching the barrel in position 5 by means of the screw threads as described, I may provide a construction such as that shown in Fig. 3, in which the head 30 is provided with a flange 32 whch projects toward the barrel. This flange 32 is provided with 10 a slot 26 having a longitudinal extension 27, a cross extension 28, and a tail or short longitudinal extension 29. The barrel is then provided with an outwardly projecting pin 31. This pin can be seated in the tail 29 by 15 giving the barrel two inward movements separated by a rotary movement, in other words the slot is simply a bayonet slot having a pocket or seat for the pin, which prevents the barrel from being rotated by the pressure 20 of the flesh upon it when the razor is in use.

Having thus described my invention, I claim as new and desire to secure by Letters Patent,—

25 1. A safety razor having a handle, a bracket attached to the end of said handle and having an offset upwardly projecting head, an electric motor seated on said bracket and having a shaft extending through said 30 head, a substantially cylindrical guard attached to the outer side of said head, and a rotary blade holder attached to said shaft within said guard.

2. A safety razor having a handle, a 35 bracket attached to the end thereof and having an offset head with a flange in the outer

face thereof, an electric motor mounted on said bracket substantially on the axis of said handle, a shaft extending through said head, a substantially cylindrical guard attached to 40 said flange and receiving said shaft, and a rotary blade holder mounted on said shaft within said guard.

3. A safety razor having a cylindrical guard with inclined slots formed therein, a 45 rotary blade holder mounted within said guard, and means for driving said blade holder.

4. In a safety razor, in combination, a blade holder consisting of curved cheek 50 plates having flanges at the edges thereof and having adjusting slots, blades having the edges thereof retained by said flanges, and a bolt connecting said blades with said cheek plates at said slots.

5. A safety razor having a cylindrical guard with perforations in the wall thereof, a rotary blade holder mounted in said guard, having curved cheek plates lying adjacent to the inner side of the wall of said guard, 60 said cheek plates having means at the ends thereof for retaining blades, blades attached on said cheek plates, and means for adjustably securing said blades to said cheek plates.

In testimony whereof I have signed my 65 name to this specification in the presence of two subscribing witnesses.

LUIGI BRUNACCI.
